UNITED STATES PATENT OFFICE.

CLARK KETCH, OF WHARTON, OHIO.

STRAW-CARRIER.

SPECIFICATION forming part of Letters Patent No. 358,042, dated February 22, 1887.

Application filed April 7, 1886. Serial No. 198,125. (No model.)

To all whom it may concern:

Be it known that I, CLARK KETCH, a citizen of the United States, residing at Wharton, in the county of Wyandot and State of Ohio, 5 have invented a new and useful Improvement in Delivery-Boards for Straw-Carriers, of which the following is a specification, reference being had to the accompanying drawings.

My invention relates to an improvement in 10 delivery-boards for straw-carriers; and it consists in the peculiar construction and combination of devices, that will be more fully set forth hereinafter, and particularly pointed out in the claim.

15 In the drawings, Figure 1 is a perspective view of my invention. Fig. 2 is a sectional view of the same.

Heretofore great difficulty has been experienced in the operation of the straw-carriers 20 of thrashing-machines, for the reason that a portion of the straw elevated by the carrier is not discharged from the outer end thereof, but becomes entangled with the carrier-slats, and is carried back thereby on the under side of the 25 carrier toward the thrashing-machine, whereby the riddles of the separator are clogged. In order to prevent this it has been heretofore necessary to station a man with a pitchfork at the discharge end of the straw-carrier in order 30 to release the straw therefrom. This defect it is the object of my invention to overcome.

A represents the carrier of a thrashing-machine, which is of the usual construction, and consists, essentially, of the endless belts B, 35 carried on rollers, and connected together by transverse slats C. To the rear end of the frame of the carrier is secured a shield, D, which extends transversely across the discharge end of the carrier, and is curved in 40 cross-section, forming the segment of a circle of sufficient size to enable the carrier-slats to pass over the upper surface successively.

E represents a delivery-board, which is hinged to the rear end of the carrier-frame, as 45 at F, while its outer or free end is adjustably supported by brace-arms G, pivotally attached to the sides thereof, near said free end, the inner ends of said braces being slotted, as at H, and secured to the sides of the carrier-frame by means of set-screws I, which pass 50 through the said slots and enter the sides of the said frame.

By means of these braces it will be readily understood that the delivery-board may be inclined to any desired angle with relation to 55 the carrier and secured in that position.

The operation of my invention is as follows: As the slats C successively arrive at the rear end of the carrier, they come in contact with the shield D, which prevents the straw from 60 becoming entangled with the slats, and causes it to fall therefrom onto the delivery-board E, which directs the straw to the top of the stack or on the ground, as may be desired, and the slats return on the under side of the carrier 65 empty and relieved of any adhering straws.

By means of this device the services of a man with a pitchfork at the discharge end of the carrier may be dispensed with.

I do not desire to limit myself to the precise construction hereinbefore described, as it is evident that modifications may be made therein without departing from the spirit of my invention.

I attach importance to the location of the 75 delivery-board hinged direct to the discharge end of the carrier, with the bottom of the delivery-board on a line with the end of the shield, as by that arrangement the two parts are caused to coact, the shield supporting the 80 slats of the carrier, as the said slats come in contact with the shield, and directing the straw so as to cause it to fall from the carrier onto the bottom of the delivery-board to be delivered to any desired point. 85

Having thus described my invention, I claim—

In combination with the carrier A, the shield D, located at the rear end of the said carrier, between the roller and below the belt, and the 90 delivery-board hinged directly to the rear end of the carrier, with its bottom substantially on a line with the end of the shield, as set forth.

In testimony that I claim the foregoing as 95 my own I have hereto affixed my signature in presence of two witnesses.

CLARK KETCH.
